LIGHT SHADE

Glenn E. MacFadden, Rocky River, Ohio

Application November 21, 1950, Serial No. 13,086

Term of patent 14 years

(Cl. D48—16)

To all whom it may concern:

Be it known that I, Glenn E. MacFadden, a citizen of the United States, residing at Rocky River, State of Ohio, have invented a new, original, and ornamental Design for Light Shade, of which the following is a specification, reference being had to the accompanying drawing, forming a part hereof:

I claim:

The ornamental design for a light shade, as shown and described.

GLENN E. MACFADDEN.
